UNITED STATES PATENT OFFICE.

HENRY ZIEMSS, JR., OF CHICAGO, ILLINOIS.

TOY.

Application filed April 29, 1920. Serial No. 377,479.

To all whom it may concern:

Be it known that I, HENRY ZIEMSS, Jr., a citizen of the United States, residing at Chicago, in the county of Cook and State of Illinois, have invented a certain new and useful Toy, of which the following is a specification.

The invention relates to toys of the type comprising a plurality of parts adapted to 10 be operatively associated in different relationships to form various devices, the several principal parts performing in each instance of use a generally similar function.

The object of the invention is to provide a combination of parts constructed in 15 such a manner as to be capable of being assembled in a variety of relationships to provide either a teeter-totter, a bench, a slide or a merry-go-round.

20 A more specific object of the invention is to provide a construction which is very simple and which presents a neat appearance and is at the same time of substantial strength and rigidity.

25 In the accompanying drawings, wherein I have illustrated a preferred form of the invention, Figures 1 and 2 are fragmentary edge and under-side elevations, respectively, of a seat member for the toy. Figs. 3 and 4 are end and side elevations, respectively, of one of a pair of standards with the braces carried thereby. Figs. 5 and 6 are side and edge elevations, respectively, of the braces. Figs. 7 and 8 are fragmentary detail views 30 showing the construction of the upper end of the other one of the aforementioned pair of standards. Figs. 9 and 10 are under-side and edge elevations, respectively, of the means for detachably securing the seat member upon the standards for rotary movement. Fig. 11 is a fragmentary side elevation of the toy assembled to provide a teeter-totter and showing in broken lines the assembly for the slide. Fig. 12 is a 35 fragmentary side elevation showing one end of the toy as it is arranged to form a bench, a slightly different arrangement being shown in broken lines to provide a lower bench. Fig. 13 is a fragmentary side elevation showing the parts assembled to form a merry-go-round. Fig. 14 is an end view 40 of the parts in the position shown in Fig. 13 but showing the seat member in section.

Referring first to Figs. 1 to 10, the combination toy comprises generally a seat member 15, a pair of standards 16 and 17

and braces 18. The seat member may be made from a board of suitable width and length and is provided centrally thereof upon its under-side with a pair of spaced 60 members or blocks 19 spaced apart so as to receive a supporting rod carried by the standards, as will presently be described.

The standards 16 and 17 each comprises a pair of upright members 20 maintained 65 in spaced relation by means of a plurality of rungs. Herein lower and intermediate rungs 21 are provided and upper rungs 21^a and 21^b for the standards 16 and 17 respectively. The uprights 20 of the respective standards are spaced apart so that the upper end of one of the standards (herein the standard 16) is capable of entering between the uprights of the other standard (herein the standard 17), and means are 70 provided for detachably securing the standards together at their upper ends. To this end the topmost rung 21^a of the standard 16 is made of such a length that its opposite ends project beyond the outer sides of 75 the uprights 20 as shown in Fig. 3; and the rung 21^b of the standard 17 is removably mounted in the upper ends of the uprights 20. Said extended end portions of the rung 21^a are flattened, as shown at 23, (Figs. 3 and 80 4) so as to be capable of entering apertures 24 in the uprights 20 of the standard 17 when the rung 21^b is removed, said uprights being provided with slots 25 (Figs. 7 and 8) communicating with the apertures 24 for 85 this purpose. It will be seen upon reference to Fig. 11 that the flattened extensions 23 and the slots 25 are relatively arranged so 90 that when the standards occupy the operative position shown in said figure, the extensions are out of register with the slots 95 and thus the standards are interlocked.

The braces 18 are pivotally mounted upon the uprights 20, one on each of the standards 16 and 17. Said braces may consist of a pair of members 26 and 27 pivotally connected together at 28. The member 26 is pivoted upon one of the uprights 20, and at its free end and also in the member 27 are provided notches 29 adapted to engage with headed studs 30 carried by the opposite standard, or with slotted straps 31 upon the under-side of the seat member 15. In order that the member 26 of the braces may have a notch 29 at its free end, the pivotal connection between the members is located at 105 a substantial distance from the free end of 110

the member 26; and to maintain the two members in their extended relation preventing them from flexing, the member 26 is provided with a laterally extending portion 5 or lug 32 adapted to engage in a notch 33 in the upper edge of the member 27.

Near its opposite ends, the seat member 15 is provided with means for detachably securing it to the opposite standards 16 and 17. Herein such means comprises U-shaped members 34 formed of sheet metal so as to be resilient and secured to the under-side of the seat member as by means of screws 35. It will be understood that these devices 34 15 are adapted to engage with the rungs of the standards 16 and 17 and yieldingly hold the seat member in position thereon.

The means for detachably securing the seat member to the standards, in providing 20 a merry-go-round, may comprise a plate member 36 having upon its under-side a pair of spaced members or blocks 37, similar to the blocks 19 upon the seat member and adapted to receive between them the uppermost rung 21^a of the standard 16 when the two standards are operatively associated as in Fig. 11. Upon the upper side of the plate member 36 a suitable anti-friction bearing may be provided consisting of a pair of 25 disk members 38 and 39 providing a raceway for a plurality of balls 40 interposed therebetween. A bolt 41 is entered vertically and upwardly through the plate member 36, the disk members 38 and 39 and a transverse member 42 upon the disk member 39, and the upper end of the bolt is adapted to be entered through an opening 43 in the seat member 15 and secured in position by means 30 of a nut 44 when the member 42 is entered between the members 18 upon the under-side of the seat member. At its opposite ends the plate member 36 has a pair of stay members 45 pivotally mounted thereon and having at their free ends rung-engaging 35 members or clasps 46 (Fig. 13) adapted to yieldingly engage with the intermediate rungs 21 so as to maintain the plate member in horizontal position.

As will be apparent from Fig. 11, the 40 standards 16 and 17 are operatively associated with their lower ends separated and their upper ends connected by the rung 21^a. In this arrangement of the parts, the braces 18 of the respective standards engage with the studs 30 upon the opposite standards to maintain the standards in the desired relationship. It will be apparent that the height of the support provided by the standards may be altered by varying the inclination 45 of the standards in accordance with the several notches 29 in the braces. With this arrangement of the standards, it will be apparent that the seat member may be supported thereby either centrally thereof as shown in full lines in Fig. 11, to form a

teeter-totter, or at one end to form a slide as shown in broken lines in said figure. For the purpose of providing a stop for the hands of a child seated upon the ends of the seat member in the case of a teeter-totter, 70 I provide a transverse strip 47 near each end of the seat member as shown in Figs. 2 and 11.

In Fig. 12 the parts are shown as they are assembled to form a bench or seat. In 75 this arrangement of parts, the members 34 on opposite ends of the seat 15 engage either with the uppermost rungs of the oppositely disposed standards 16 and 17 to provide a bench of the greatest elevation, or with the 80 intermediate rungs of the standards to provide a lower bench. In the first instance the braces 18 are extended to provide a connection between the seat member and the standards, the free ends of the members 27 85 of the braces engaging in the slots 49 in the straps 31. As shown in Figs. 1 and 2, the straps 31 may consist of angular plates secured in position as by means of screws 48 and having its slots 49 disposed diagonally 90 so as to receive the ends of the braces 18 when the latter are flexed inwardly thereto. The pivotal connection of the braces 18 with the uprights 20 of the respective standards may also conveniently be loose enough to 95 permit sufficient side swinging of the braces so that they may be connected with the straps 31. As shown in broken lines in Fig. 12, when the seat member is mounted upon the intermediate rungs 21 of the standards, the sections 26 only of the braces are employed, the notches 29 in their free ends being engaged in the straps 31.

When the parts are to be assembled for use as a merry-go-round, the standards are 100 relatively arranged as in the case of the teeter-totter and the slide, and the plate member 36 is mounted upon the rung 21^a of the standard 16 with the free ends of the plate supported by the members 45 having 105 their clasps 46 yieldingly engaging with the intermediate rungs 21 of the standards. The seat member is then placed in position upon the anti-friction bearing with the member 42 thereof entered between the members 19 110 upon the under-side of the seat member, and with the bolt 41 entered through the opening 43 in the seat member, the parts being secured in operative relation by the nut 44.

It will be seen that I have provided a 115 combination toy which is readily adapted to be assembled in a variety of forms to provide a number of different toys. The construction is rigid and durable and the parts are capable of being easily assembled and 120 disassembled to suit the whims of the child. It will be understood, however, that the invention is not limited to the particular construction and arrangement shown since it is contemplated that various changes may be 125

made without departing from the spirit and scope of the invention.

I claim as my invention:

1. In a combination toy, a pair of standards each comprising two upright members and means connecting said members together in spaced relation, said means including a plurality of rungs, one of said standards having a rung removably mounted in its upper end, and the other one of said standards having a rung fixedly mounted in its upper end, the last mentioned rung being adapted to operatively engage with the upper end of the opposite standard when the removable rung has been removed, and a seat member adapted to be supported upon one or more of said rungs either centrally or at one or both ends of the seat member.

2. A combination toy having a pair of standards each comprising two upright members and means connecting said members together in spaced relation, said means including a plurality of rungs, one of said standards having a rung removably mounted in its upper end, and the other one of said standards having a rung fixedly mounted in its upper end, the last mentioned rung being adapted to operatively engage with the upper end of the opposite standard when the removable rung has been removed, and a seat member adapted to be supported upon one or more of said rungs either centrally or at one or both ends of the seat member, said standards each having a pivoted member or brace and a detachable connection member adapted to be engaged by the brace of the opposite standard, and said seat member having a pair of detachable connection members adapted to be engaged by said braces.

3. The combination of a pair of standards each having a plurality of supporting mem-

bers arranged at different heights, a seat member adapted to be supported at its opposite ends by said supporting members, and 45 braces each comprising two pivoted sections one of which is arranged to connect the seat member and a standard at one elevation of the seat member, and both of which are adapted when extended to connect the seat 50 member and a standard at a higher elevation of the seat member.

4. The combination with a pair of standards and a seat member, a brace between any two of the parts comprising two sections one 55 of which is pivoted to one of the parts and has its free end notched, and the other one of which is pivoted to the first section at a point spaced from its free end and also has its free end notched, said sections being 60 adapted to coact to prevent flexing of the brace, and means upon the other one of said parts adapted to be engaged by one or the other of said notched ends.

5. A combination toy comprising, a seat 65 member, a pair of supporting standards, co-operating means on the standards and said seat member whereby the seat member may be supported on the standards in one or more positions, and brace members carried by each 70 standard and adapted to detachably engage with the other standard or the seat member, the arrangement being such that when the standards are connected together by said brace members they serve to coact to support the seat member at one point in its length, and when the standards are secured by the brace members to the seat member they serve to support the latter at spaced 75 points in its length. 80

In testimony whereof, I have hereunto set my hand.

HENRY ZIEMSS, JR.
